UNITED STATES PATENT OFFICE.

EDWARD W. WHITTAKER, OF NEW YORK, N. Y.

DESIGN FOR A SUSPENDER-END.

SPECIFICATION forming part of Design No. 19,268, dated August 13, 1889.

Application filed July 1, 1889. Serial No. 316,237. Term of patent 7 years.

To all whom it may concern:

Be it known that I, EDWARD W. WHITTAKER, a citizen of the United States, residing at the city, county, and State of New York, have invented and produced a new and original Design for Suspender-Ends, of which the following is a specification, reference being had to the accompanying drawing, forming part thereof.

10 The figure is a front view of a suspender-end showing the design.

The leading feature of the design consists of an inverted-U-shaped suspender-end A, the middle portion B of which is round and continued into the almond-shaped parts C C, from

which extend the sides D D of the U-shaped end A. Each side D D is formed at its outer end into loops E. Part of the round middle portion B is surrounded by a band F, having curved sides and straight ends and a curved line G on its face. The upper end of the band F is linked with an ordinarily-shaped buckle H.

I claim—

The design for a suspender-end herein shown and described.

EDWARD W. WHITTAKER.
